UNITED STATES PATENT OFFICE

2,518,830

HYDRAULIC PUMP AND MOTOR

Franklin E. Staats, Keithsburg, Ill.

Application October 15, 1947, Serial No. 780,057

4 Claims. (CL 103—38)

1

This invention relates to hydraulic pumps and motors and more particularly to an improved hydraulic pump having a variable throw crank-shaft and pressure responsive means associated with the output of the pump for effecting changes in the crankshaft throw.

It is an object of this invention to provide an improved pump of the kind to be more specifically described hereinafter having radially disposed pumping cylinders with pistons connected to a common crank pin and valves for each cylinder operated by means connected to a crank pin fixed to the piston crank pin and eccentric thereto.

Another object of this invention is to provide radial hydraulic pump having a drive shaft with a movably mounted double eccentric crank pin and a piston about the crankshaft operative to vary the eccentricity of the crank pin relative to the axis of the crankshaft. The crank pin operating piston is so constructed and arranged that its movement will be affected by the demand for maintaining a constant output pressure.

A further object of this invention is to provide a constant speed pump for delivering a constant pressure, the pump being so constructed that variations in demand will affect the stroke of the pumping pistons to maintain a substantially equal output pressure.

A further object of this invention is to provide a constant speed pump for automatically delivering a variable pressure, the pump being so constructed that variations of the load will affect the stroke of the pumping pistons and automatically furnishing the proper output pressure.

Yet another object of this invention is to provide a valve operating means directly associated with the crank pin of the radial pump for operating the valves in synchronism with the rotation of the crank pin in all positions of the crank pin relative to the axis of the drive shaft.

With the above and other objects in view, my invention consists in the arrangement, combination and details of construction disclosed in the drawings and specifications, and then more particularly pointed out in the appended claims.

In the drawings:

Figure 1 is a longitudinal section taken through a pump constructed according to an embodiment of this invention.

Figure 2 is a transverse section taken on the line 2—2 of Figure 1.

Figure 3 is a transverse section taken on the line 3—3 of Figure 1.

Figure 4 is a fragmentary detailed section taken on the line 4—4 of Figure 1.

2

Figure 5 is a fragmentary detailed section taken on the line 5—5 of Figure 1.

Figure 6 is a fragmentary section taken on the line 6—6 of Figure 1.

Figure 7 is a fragmentary transverse section partly broken away, taken on the line 7—7 of Figure 1.

Figure 8 is a transverse section taken on the line 8—8 of Figure 1.

Figure 9 is a fragmentary detailed section taken on the line 9—9 of Figure 1.

Figure 10 is a plan view of the locking ring removed from the pump.

Figure 11 is a fragmentary enlarged detailed section of the locking ring and nut on the drive shafts.

Figure 12 is a longitudinal section of a modified form of this invention as related to a liquid driven engine.

Referring to the drawings, the numeral 20 designates generally a hydraulic pump which is adapted to be driven at a constant speed and is provided with means for maintaining the output pressure at a constant pressure irrespective of the use of the outlet fluid and for maintaining a constant fluid pressure whether units driven by the pump are being operated or not.

The pump 20 is formed of a substantially hemispherical housing 21 open at one end and a cover plate or closure 23 for closing the open end. A circumferentially disposed inlet passage is formed in the housing 21 substantially in the center thereof, and an annular circumferentially disposed outlet passage is formed in the housing rearwardly of the inlet passage.

The housing 21 is also formed with a series of forwardly opening bores 25 near the front end thereof for supporting oscillating valves therein. The inlet passage 22 and outlet passage 24 are communicated with the valve bore 25 by forwardly extending passages 26 and 27 respectively. The inlet passage 26 between the valve bore 25 and the passage 22 extends forwardly to communicate with the front end of the valve. The outlet passage 27 between the passage 24 and the bore 25 terminates in the bore 25 adjacent the rear end thereof.

A valve 28 is rockably supported within the bore 25 in an apertured sleeve or bearing 29. The bearing 29 is fixed in the bore 25 and formed with circumferentially disposed openings 30 which open into the inlet passage 26. The valve 28 is formed of a tubular sleeve 31 rotatable in the bearing 29 and extending along the length thereof. The valve sleeve 31 is formed with a vertical

wall 32 intermediate the length thereof for separating the inlet and outlet chambers communicating therewith.

The sleeve 31 is formed with an opening 34 on one side thereof communicating with the opening 30 in the sleeve 29 for admitting the fluid from the inlet passage to the valve. The sleeve 29 is formed with openings 35 opening into a passage 36 which extends from the valve to the cylinders 37 in the housing 21. The sleeve 31 is formed with openings 38 which are adapted to register with the openings 35 in one position of the sleeve 31 for permitting the flow of fluid from the inlet passages to the cylinder.

The opening 34 is adapted to register with the opening 30 in the sleeve 29 for permitting a flow of fluid therethrough in all positions of the valve 28. The inlet openings of both the sleeve 29 and sleeve 31 are disposed forwardly of the central wall 32 of the valve. The valve 28 rearwardly of the wall 32 is formed with openings communicating with the outlet of the pump. The sleeve 31 rearwardly of the wall 32 is formed with openings 39 which are adapted to register with openings 40 in the bearing 29 to provide an outlet port or valve for the cylinder.

An opening 41 in the sleeve 31 is adapted to register with an opening 42 in the sleeve 29 for providing an outlet for the fluid from the cylinder through the valve 28 into the outlet passage 27. An externally opening outlet passage 44 is formed in the housing 21 at the top thereof, communicating with the annular outlet passage 24.

The passage 44 is adapted to be connected by suitable fluid conducting pipes to hydraulically operated devices. The radially disposed cylinders 37 formed in the housing 21 are each communicated with the inlet and outlet passages of the pump 20 by valves and passages as described above.

Pistons 45 are slidably disposed in each of the cylinders 37 and are connected to a central bearing 46 in a recess 47 at the front end of the housing 21. One of the pistons 45a is considered the master piston and is connected to the main bearing 46 by a connecting rod 48 which is pivotally connected to the piston by a pin 49 and fixed on the bearing 46 as by the pin 50. The remaining pistons 45 are connected to the main bearing 46 by connecting rods 51 which are pivotally connected to the piston by pins 52 and pivotally connected to the bearing 46 by pins 54.

The connecting rods 51 are designated as articulated rods while the rod 48 is designated as a master connecting rod. The valve sleeves 31 are extended forwardly beyond the front end of the pump body 21 and are adapted to engage in recesses in the cover 22. The valve 28 is supported in the housing 21 and cover 22 by roller bearings as 55.

A transverse or diametric opening is provided in the valve 28 forwardly of the housing 21 in the space between the front end of the housing and the cover 22. A valve operated pin 56 is slidably disposed through the opening 57 in the valve. The valve pin 56 is pivotally connected to a bearing 57 to be operated in conjunction with the main bearing 46 described above.

A pin 56 is provided for each of the valves 28, and one of the pins 56a is constructed as a master pin, while the other pins 56 are pivotally connected to the bearing 57 as articulated pins. The bearing 57 is provided with a pair of radially extending longitudinally spaced apart flanges 58 about the center hub 59. The pins 56 are pivotally connected by the bearing 57 by pins 60 en-

gaging through the flanges 58. The master pin 56a extends inwardly beyond the pin 60 into an arcuate recess 61 in the hub 59.

The extension 62 of the pin 56a is adapted to engage in the arcuate recess 61 for permitting the master pin 56a a certain degree of rocking movement for timing the valves in relation to the crankshaft and in relation to the pistons of the pump.

As the bearing 57 is caused to rotate by the drive shaft which also oscillates the main bearing 46, the valve movement will be offset in a definite timing relation as the master pin 56a is rocked to an extreme position in the slot or recess 61.

When the extension 62 engages the edge of the recess 61, all of the valves will be actuated in timed relation to the pistons with the desired lag furnished by the size of the recess 61.

A crankshaft 70 is provided in the pump 20 for reciprocating the pistons 45 and actuating the valves 28. The crankshaft 70 is adapted to be rotated at a constant speed from an external source of power, and is formed of a drive shaft 71 and a driven shaft 72 connected at the front end thereof.

The front or driven shaft 72 is mounted eccentric to the drive shaft 71. The drive shaft 71 is rotatably supported in the rear end 74 by bearings 75, and a sealing member 76 is carried by the cover 74 between the bearing 75 and the opening through which the drive shaft 71 extends. The drive shaft 71 extends forwardly substantially to the center of the housing 21 where it is formed with an enlarged disk 77 thereon. A hollow or tubular connecting member 78 is fixed to the disk 77 by recessed screws 79 or other suitable fastening devices, and extends forwardly of the disk 77.

The connecting member 78 is eccentric to the shaft 71. The forward end of the sleeve 78 is reduced in diameter as at 80, and roller bearings 81 journal the reduced end of the connecting member in the housing 21. The connecting member 78 is rotated with the drive shaft 71, and is further connected thereto by keys 82 engaging in keyways 84 of a forwardly extending reduced diameter sleeve 85 fixed to the front end of the disk 77 within the connecting member 78. The opening in the sleeve 78 adjacent the drive shaft 71 is enlarged for housing the enlarged end of the driven shaft 72, and the outer end of the sleeve 78 is reduced to form a bearing for the intermediate portion 86 of the driven shaft. The driven shaft 72 is disposed eccentrically to the drive shaft 71, in the connecting member 78.

The intermediate portion 86 of the driven shaft 72 is rotatably journaled in a bushing 87 carried by the connecting member 78 in the outer end thereof. The enlarged end 88 of the driven shaft 72 is disposed immediately adjacent to the disk 77, fixed on the drive shaft 71. The enlarged portion 88 is formed with helical keyways 89 therein, for engagement with means to be later described, for rotating the driven shaft 66 relative to the drive shaft. The end of the driven shaft 72, adjacent the drive shaft 71, is journaled in a bearing 90 fixed in the disk 77. A bearing 91 is provided about the intermediate portion 86 of the driven shaft within the connecting member 78. A crank pin 92 is fixed to or formed on the forward end of the driven shaft 72 eccentric thereto. The crank pin 92 is provided for engagement in a bearing 94 carried by the main piston bearing 46.

An offset crank pin 95 is fixed to or carried by

the main crank pin 92 at the outer end thereof, for oscillating the bearing 57. The valve operating bearing 57 is oscillated by rotation of the offset 95 in a bearing 96 carried by the center of the bearing 57. The offset 95 is disposed eccentric to the axis of the crank pin 92, and offset eccentrically relative to the longitudinal axis of the driven shaft 86.

As thus far described, the driven shaft 72 is free to rotate relative to the drive shaft 71. For 10 rotation of the driven shaft by the drive shaft, a connecting member 100 is provided. The connecting member 100 is formed of a sleeve 101 disposed about the drive shaft 71, rearwardly of the disk 77. The sleeve 101 is rotatably mounted on a bushing 102 about the shaft 71. A disk 104 is fixed on the front end of the sleeve 101 and a pair of forwardly extending arms 105 are fixed to or formed on the forward side of the disk 104.

The arms 105 extend forwardly through openings 106 in the disk 77, fixed on the drive shaft 71. Inwardly extending lugs or keys 107 are fixed to or formed on the forward end of the arms 105 for sliding engagement in the splines or keyways 89.

The connecting member 100 is free to slide along the length of the drive shaft 71, and free to rotate thereon. The rotation of the connecting member 100 is limited only by the engagement of the keys 107 in the splines 89. As the connecting 30 member 100 is moved along the axis of the drive shaft 71, the engagement of the keys 107 in the helical splines 89 cause rotation of the driven shaft 72 relative to the drive shaft 71.

As the driven shaft 72 is rotated relative to the axis of the drive shaft 71, the crank pin 92 and offset 95 are moved radially relative to the axis of the drive shaft 71, by virtue of the eccentric disposition of the driven shaft 72.

The pump 20 is designed so that a constant pressure will be delivered from the pump while the drive shaft 71 is turned at a constant speed. In order to vary the output pressure while the shaft 71 is rotating constantly, it is necessary to rotate the driven shaft 72 to a position where the movement of the pistons 45 in the cylinders 37 will be reduced or enlarged according to the requirements of the output pressure. As the driven shaft 72 is rotated by sliding movement of the connecting member 100 on the drive shaft 71, the axis of rotation of the crank pin 92 and offset 95 is moved inwardly and outwardly for varying the throw of the pistons. In order to provide for the automatic movement of the driven shaft relative to the drive shaft in relation to the output pressure, there is provided an operating cylinder 110 in the rear end of the housing 21, connected to the connecting member 100. The cylinder 110 is disposed concentrically about the drive shaft 71 and is journaled about the connecting member 100 by 40 thrust bearings 111 and 112.

The outer race of the bearings 111 and 112 are carried by the piston 110, and the inner race is carried by the connecting member 100. The bearings 111 and 112 are so constructed and arranged that the connecting member 100 is free to rotate within the piston 110, and axial movement of either the connecting member 100 or the piston 110 will effect sliding movement of the other. Springs 114 are provided between the rear end of the piston 110 and the inner surface of the rear cover 74. The springs 114 constantly bias the piston forwardly in the cylinder 115. Piston rings 116 are provided about the piston 110 for engage-

ment with the cylinder walls 115 for sealing the piston therein.

The cylinder 115 is provided with an annular recess or groove 117 about the rear end thereof, and the piston 110 is provided with an enlarged shoulder 118 in slidable engagement with the wall of the enlarged portion 117. The space between the reduced end of the cylinder 115 and the shoulder 118 on the piston provides the chamber about the piston 110 into which pressurized fluid is adapted to be contained for sliding the piston 110 against tension of the springs 114. The housing 21 is formed with a passage 120 between the outlet passage 24 and the chamber 119 formed about the piston 110, for admitting fluid under pressure into the chamber for exerting a force against the shoulder 118. A nut 121 is provided for engagement about the sleeve 101 for securing the bearings 111 and 112 on the member 100 about the shaft 71.

The nut 121 is locked against rotation by a lock washer 122 engaging in a recess 124 in the sleeve 101, and in the recess 125 in the periphery of the nut. A lug 126 is formed on the outer periphery of the locking ring 122 for engagement in the recess of the nut and an inwardly extending lug 127 is formed on the ring 122 for engagement in the recess 124.

In the use and operation of this pump 20, fluid is admitted through a boss 128 on the side of the housing 21 into the inlet passage 22. The fluid then flows through the passages 26 into the valve 28; from the valve 28 the fluid flows through the passage 36 into the cylinders 37. Leaving the cylinders 37 under pressure, the fluid flows through a passage 43 into the valve 28.

The fluid then flows out the passages 27 and 24. The fluid is contained also within the passage 120 and in the chamber 119 under the outlet pressure. The desired pressure which is to be maintained by the pump is determined by the tension of the springs 114. As the outlet pressure decreases, the springs 114 will slide the piston 110 forwardly carrying with it the connecting member 100 which in turn will rotate the driven shaft 72 relative to the drive shaft 71, for increasing the stroke of the pistons 45.

Rotation of the driven shaft 72 will effect the radial displacement of the crank pin 92 relative to the axis of the drive shaft 71 so that a greater throw is provided for the pistons 45. Since the drive shaft 71 is rotating at a constant speed, an increase in the length of the stroke of the pistons 45 will decrease the pressure output. This will then increase the volume and decrease the pressure output.

Similarly, as the output pressure increases, the piston 110 will be moved rearwardly and the stroke of the pistons 45 will be shortened so that less fluid is pumped from the cylinders 37 while the crankshaft 70 is rotating at a constant speed.

In Figure 12 there is shown a modified form of this invention which is particularly applicable to a motor to be driven by a pump of this kind. The motor 140 is formed of a housing 21a similar to the housing 21 of the pump 20. Annularly disposed inlet and outlet passages 23a and 24a are formed in the engine 140 and are connected to the cylinders 37a through valves 28a, similar to the valves described in the pump above.

The drive shaft 70a of the motor 140 is formed in one piece, having an offset crank pin 92a and an offset 95a for separating the valves 28a. The operation and construction of the valves 28a is

identical to the construction and operation described above for the pump 20.

No means is provided in the motor 140 for varying the throw of the crank pins as the demand from the motor will be taken care of and satisfied by the automatic control in the pump 20 which is adapted to furnish the proper pressure in the lines between the pump 20 and the motor 140, causing the motor to deliver the proper torque at the proper speed of the load for the input horse power.

I do not mean to confine myself to the exact details of construction herein disclosed, but claim all variations falling within the purview of the appended claims.

Having thus described my invention, what I claim is:

1. A constant speed and constant delivery-pressure pump comprising a housing, cylinders in said housing, pistons slideable in said cylinders, a crankshaft journaled in said housing, said housing formed with inlet and outlet passages communicating with said cylinders, said crankshaft including a drive shaft, a driven shaft eccentric to said drive shaft, a slideable coupling between said latter shafts, a bearing member for said crankshaft concentric to said drive shaft about said driven shaft and journaled in said housing, an eccentric crank pin on said driven shaft extending beyond said bearing member, a helical sliding connection between said driven shaft and said coupling whereby said driven shaft will be rotated in said bearing member and circumferentially displaced relative to said drive shaft upon sliding of said coupling, and means actuated by the fluid outlet pressure for sliding said coupling thereby varying the crank pin relative to the axis of the crankshaft.

2. A constant speed and constant delivery-pressure pump comprising a housing, cylinders in said housing, pistons slideable in said cylinders, a crankshaft journaled in said housing, said housing formed with inlet and outlet passages communicating with said cylinders, said crankshaft including a drive shaft, a driven shaft eccentric to said drive shaft, a slideable coupling between said latter shafts, a bearing member concentric to said drive shaft about said driven shaft and rotatable in said housing, an eccentric crank pin on said driven shaft extending beyond said bearing member, said driven shaft formed with a helical groove thereabout, a coupling member slideable on said drive shaft and engaging in said groove whereby said driven shaft will be rotated in said bearing member upon sliding of said coupling member, a cylinder in said housing about said drive shaft, said housing formed with a passage between said latter cylinder and said outlet passage, a spring-pressed piston in said latter cylinder fixed on one end of said coupling member, and opposed thrust bearings carried by said latter piston and said coupling member for sliding said latter piston and said coupling together while permitting the rotation of drive shaft therein.

3. A constant speed and constant delivery-pressure pump comprising a housing, cylinders in said housing, pistons slideable in said cylinders, a crankshaft journaled in said housing, said

housing formed with inlet and outlet passages communicating with said cylinders, said crankshaft including a drive shaft, a driven shaft eccentric to said drive shaft, a slideable coupling member on said drive shaft, a bearing member concentric to said drive shaft about said driven shaft and journaled in said housing, an eccentric crank pin on said driven shaft extending beyond said bearing member, said driven shaft formed with a spiral groove within which said coupling member is engaged whereby said driven shaft will be circumferentially displaced relative to said drive shaft upon sliding of said coupling member, a cylinder in said housing about said drive shaft, said housing formed with a passage between said latter cylinder and said outlet passage, a spring-pressed piston in said latter cylinder, and opposed thrust bearings carried by said latter piston and said coupling member for sliding said latter piston and said coupling member together while permitting the rotation of said coupling member therein, whereby an increase of pressure in said outlet passage caused by decrease in demand will effect sliding of said latter piston against the spring tension for decreasing the throw of said pistons and decreasing the volume and outlet pressure of said pump.

4. A constant speed and constant-delivery-pressure pump comprising a housing, radially disposed cylinders in said housing, pumping pistons slideable in said cylinders, a crankshaft including a drive shaft and a driven shaft, a driven shaft bearing in said housing concentric with said drive shaft, said driven shaft rotatably engaging in said bearing eccentric thereto, a coupling member slideable on said drive shaft engaging in a helical groove on said driven shaft, a crank pin on said driven shaft and a main bearing on said crank pin connected to said pistons, a spring-pressed piston slideable on said drive shaft connected to said coupling member, said housing formed with an outlet passage from said cylinders communicating with a cylinder about said drive shaft for sliding said latter piston in response to variations in demand thereby rotating said driven shaft in said bearing and rocking said crank pin radially relative to the axis of said drive shaft and driven shaft bearing for varying the throw of said pumping pistons.

FRANKLIN E. STAATS.
